(57) **CLAIM**

The ornamental design for a keycap, as shown and described.

DESCRIPTION

FIG. 1 is a perspective view of a keycap showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The inverted triangle strip section of the keycap seen in FIGS. 1-3, 5 and 6 is transparent.

1 Claim, 6 Drawing Sheets
